UNITED STATES PATENT OFFICE.

ELLSWORTH A. HAWTHORNE, OF BRIDGEPORT, CONNECTICUT.

DESIGN FOR A MOUNTING FOR LAMPS AND LAMP-SUPPLY CONTAINERS.

46,092.

Specification for Design.

Patented July 14, 1914.

Application filed May 19, 1914. Serial No. 839,657. Term of patent 14 years.

To all whom it may concern:

Be it known that I, ELLSWORTH A. HAWTHORNE, a citizen of the United States, and a resident of Bridgeport, in the county of Fairfield and State of Connecticut, have invented a new, original, and ornamental Design for a Mounting for Lamps and Lamp-Supply Containers, of which the following description, in connection with the accompanying drawings, is a specification.

The drawings show in perspective a mounting for lamps and lamp supply containers embodying the invention.

I claim:

The ornamental design for mounting for lamps and lamp supply containers, as shown. In testimony whereof, I have signed my name to this specification, in the presence of two subscribing witnesses.

ELLSWORTH A. HAWTHORNE.

Witnesses:

E. HORACE HAWTHORNE,
